VENTING DEVICE FOR DIE CASTING MACHINES

Fritz Hodler, Territet, Switzerland

Application January 20, 1958, Serial No. 710,085

Claims priority, application Switzerland October 1, 1957

6 Claims. (Cl. 22—73)

The present invention relates generally to die casting machines and more particularly to improvements in venting devices for dies in die casting machines of the type in which the die has means for evacuating the air and gases from the die cavity. The evacuating means are characterized by the use of valve means designed to be closed when the die cavity is filled with metal.

Die casting machines of this general type are well known in the prior art and having been described in my prior U. S. Patent #2,785,488.

Although the valves controlling the evacuation of the dies of the machines of the prior art operate satisfactorily, their mounting on one of the die halves offers certain difficulties because of lack of convenient space and because of unfavorable heat conditions which tend to deteriorate the packing used in these valves. Furthermore any repair or maintenance work on the valve necessitates taking the die half from the machines, which especially in the case of large sized dies is a great inconvenience.

It has been found that although the adaptation of the valve to the die is generally possible in the case of new dies which can be designed accordingly, this adaptation is often unpractical in the case of existing dies in current use which are quite hard and extremely difficult to machine. Also any machining or welding of hardened dies carries the risk of setting up new tensions and distortion which should, of course, desirably be avoided.

The object of the present invention is to avoid these inconveniences by the use of a valve which is independent of the die and not connected with the same, this valve being mounted on the frame of the die casting machine. The valve is provided with means for bringing it into contact with the die prior to the casting operation, and for moving it away from the die when the injection is terminated. The valve is also provided with means for controlling these movements and for allowing the air and gases to be evacuated from the die cavity and has means for insuring the closing of the air channel of the die at the required time during the injection cycle. A further advantage of my invention is then in order to adapt a die to be used in connection with this valve, only a small channel has to be ground in the die, which is possible also in the case of hardened dies, and also regulation of the closing time of the valve may be made possible without removing the die from the machine.

Another advantage of my invention is that maintenance and repair of the valve is greatly facilitated since the valve forms a separate unit attached to the die casting machine. It is also clear that the same valve can be used in connection with a great number of dies. Also the valve can be mounted on the frame of the machine at any place to suit the design and the size of the die.

Still another advantage of my invention is that the

2

capacity of the air passage can easily be adapted to the volume of the die and the die cavity in order to insure proper evacuation.

The foregoing objects, with others that will appear as this description proceeds, are attained in the embodiment of the invention illustrated in the accompanying drawings wherein:

Fig. 1 shows diagrammatically part of the hydraulically operated pressure die casting machine in the position when the die as well as the venting device are closed.

Fig. 2 shows diagrammatically one of the die halves with an air outlet channel.

Fig. 3 shows the same arrangement as Fig. 1, but in the position when the die is open.

Fig. 4 shows diagrammatically a horizontal section of the venting device in the position when the die is open.

Fig. 5 shows the same section as Fig. 4, but in the position when the die is closed, but before the valve is closed.

Fig. 6 shows the same section as Figs. 4 and 5, but in the position when the valve is closed.

Referring to Fig. 1 the pressure die casting machine 25 consists of a frame 1 on which is mounted the die 2 consisting of the two die parts 3 and 4. These parts 3 and 4 are held together by means of a locking device. This device, which in general has a toggle mechanism, is by way of simplification shown as a hydraulic cylinder 5, in which the differential piston 6 can slide, this piston acting through a rod 7 on a locking member 8, which is designed to hold the part 3 tightly pressed against part 4 of the die which itself is fixed to the frame of the machine. This locking member 8 is in general supported by rods (not shown) which slide in bearings in the frame of the machine. Part 3 of the die has bores for the rods 3a of an ejecting device which is known and is therefore not shown in detail or described.

40 The frame 1 has an injection sleeve 9 in which the molten metal can be poured through the opening 10. This metal can be pressed in the cavity 11 of the die 2 by the injection piston 12, which, by means of the rod 13 is connected to the plunger 14 which slides in the cylinder 15.

The piston 6 and the plunger 14 are actuated by hydraulic pressure which is supplied from the control station 16 of the machine by a conduit system to the cylinders 5 and 15. Fluid under pressure, which by way 50 of example may be supplied by a pump, is supplied to the control station 16 of the machine by means of conduit 17. From here the conduit 18 connects the control station with the cylinder 5 in order to apply pressure to one face of the piston 6 to effect closing of the die 2. By means of conduit 19 liquid under pressure is fed without interruption to the opposite face of the piston 6 in order to cause opening of the die 2. A conduit 20 connects the control station 16 with the cylinder 15 in order to feed liquid under pressure into it during the injection phase. A conduit 21 is designed to feed liquid under pressure to the plunger 14 in order to make it move in the opposite direction when the injection piston is to be returned to its initial position.

65 The die 2 has a channel 22 therein allowing the air and gases contained in the die cavity 11 and the injection sleeve 9 to escape during the injection phase while the metal is entering the die. This channel 22 is connected with the conduit 23 which communicates with vacuum installation 64 whereby a vacuum may be created in the die cavity 11 prior to the injection of metal therein. A valve 24 controls the passage in the

channel 22 so as to shut off this channel as soon as the die cavity 11 is filled with molten metal.

In the example given, this valve 24 is operated by hydraulic pressure by means of the conduit 25 connected to the conduit 20 in the manner described in my U. S. Patent #2,785,448.

The different phases of the operation of the machine are controlled by means of the control lever 26 which has 3 positions designated at I, II and III.

The part of the machine which differs essentially from the parts described in the prior art referred to above is the special structural arrangement of the valve 24. This valve is mounted in a central body 27 (Figs. 4-6) which is independent of the die 2. This central body 27 is itself movable in relation to the frame 1 of the machine in such a manner as to allow it to be brought into contact with die 2 during the casting operation and to be removed from the die 2 after the casting operation. Suitable control means are provided for bringing the valve 24 in the required closing position of the channel 22 at the desired moment during the casting operation.

In the arrangement shown by way of example in Figs. 4-6, the valve 24 is located at the interior of cylindrical member 28, which has the general shape of a bell. This member 28 forms part of the central body 27 and has a face 29 designed to be brought into close contact with the die 2 during the casting operation in such a manner as to surround the orifice 30 of the air escape channel 22.

As shown in Figs. 4-6, the movable central body 27 forms a differential piston with one face of larger diameter 32 and on the opposite side a face of smaller diameter 31. This differential piston 27 slides in the corresponding cylinder 33 which forms the main valve body, which body is fixed to frame 1 of the machine by means of the lugs 34. The bore 35 of the cylinder 33 in which slides the face of the smaller diameter 31 of the differential piston 27, is closed by means of the screw plug 36. This part 35 is connected through opening 37 in the cylinder wall and conduit branch 37' to conduit 18 which feeds the cylinder 5.

A packing 38 ensures the pressure tight joint between the face 31 of the differential piston 27 and the wall of bore 35 of the cylinder 33. Cylinder 33 has another bore of larger dimensions 39 in which is located the face 32 of the differential piston. The packings 40 and 41, kept in position by the guide rings 42, 43 and 44, ensure a pressure tight joint between the wall of bore 39 and the differential piston 27. The guide ring 43 is supported by the screw ring 45 which is threadably mounted in the cylinder 33. The bore 39 of cylinder 33 is connected with conduit 19 by means of lateral opening 46 in the cylinder wall and conduit branch 46'.

The valve 24 consists of a rod actuated by a piston 47 sliding in a cylinder bore 48 of the central body 27. This cylinder bore 48 is closed at its extremity by the bell-shaped member 28 which has a threaded extension 49 screwed into bore 48. The piston 47 is held in the open position of the valve 24 under the influence of spring pressure, shown diagrammatically as a single cylindrical helical spring 50. Regulating means make it possible to vary the force exercised by the spring 50. In this particular case these regulating means consist of a screw bushing 51 which is screwed in the central part of the bell-shaped part 28 and which contacts one end of the spring 50. The exterior part of this bushing 51 is shaped in such a manner that it can be rotated by means of a suitable tool to adjust the position of the bushing longitudinally.

A channel 53 is provided in the wall of central body 27 and connects the left hand part of the cylinder 48 with the conduit 20 by means of coupling 54 and branch line 25. The piston 47 has a pressure tight packing 55.

The face 29 of the bell-shaped member 28 is formed

by member 56 which is screwed onto the body of the bell-shaped member 28. A filter 57 is fastened intermediate parts 28 and 56 and has an opening in the middle thereof through which the valve rod 24 can pass.

As shown in Figs. 4-6, the valve 24 is arranged in such a manner as to have its longitudinal axis parallel with the contact surface 58 of the die halves 3 and 4 of the die 2, this axis being perpendicular to the face 59 of the die in which the channel 22 is located.

The operation of the machine described above may now be readily presented:

When the operator of the machine moves the control lever 26 from the position I to position II, liquid under pressure will flow in conduit 18. The piston 6 will then be moved to the right against the pressure of the liquid acting on the other face of the piston 6 supplied through conduit 19 to cause locking member 8 to be displaced so that parts 3 and 4 of the die 2 are brought into contact with one another. At this moment the pressure in the closing cylinder 5 will be increased to cause longitudinal displacement of the differential piston 27 and of the bell-shaped member 28 thereon toward the face 59 of the die 2. This hydraulic pressure in the cylindrical part 35 exercises a strong pressure on the bell-shaped member 28 to firmly force it against the face 59. Ring 61, which may be formed from aluminum for example, ensures a pressure tight joint between the face of the bell-shaped member and the face 59 of the die 2.

The conduit 23 which is in communication with the interior of the bell-shaped member 28 by means of a channel 62 enables the vacuum installation 64 to create a vacuum in the cavity 11. As soon as the operator has poured a quantity of molten metal in the injection sleeve, he moves the control lever 26 from position II to position III. In this position the conduit 18 is always under pressure to ensure locking of the die halves 3 and 4 and conduit 20 transmits fluid under pressure. The actual injection phase commences by the displacement of the plunger 14 in the cylinder 15, which causes forward movement of the injection piston 12 in sleeve 9 toward the die part 3. The pressure in conduit 25 will also be increased but valve 24 will not be moved to a position closing channel 22 until the pressure in conduit 25 reaches a value which is greater than the spring force exercised by the spring 50. Since this force can be adjusted by means of the bushing 51, it is possible to chose the moment of the closing of the channel 22 by the valve 24 in such a manner that it occurs after the molten metal has passed the restricted passage 63 of the channel which conducts the molten metal to the die cavity 11, preferably when the injection phase is terminated. When the frictional losses due to the passage of the molten metal through the restricted passage 63 cause an increase in pressure in conduit 25 which is high enough to overcome the spring force exercised by the spring 50, the valve rod 24 will be displaced in the direction of the surface 59 to close the orifice of channel 22 as shown in Fig. 6.

When the injection phase is terminated, the operator will bring the control lever 26 from position III to position I. In this position the hydraulic fluid in conduits 18 and 20 can escape through conduit 60, whereas the conduit 21 is filled with fluid under pressure. The pressure which is continually exercised on the face 32 of the differential piston 27 and on the face of smaller diameter of the differential piston 6 by fluid in conduit 19 and conduit branch 46' then causes a displacement of the piston in the opposite direction. The ratio of the surface area of the two opposed faces of the differential piston is chosen in such a manner as to cause the differential piston 27 to be removed from the die 2 before the two die parts 3 and 4 are moved apart in order to avoid possible wear of the ring 61.

When the fluid in conduit 20 is allowed to escape, a lowering of pressure will occur at the same time in the conduit 25 to return valve 24 to its initial position.

Moreover, the pressure acting in the cylinder 15 through the conduit 24 will bring the injection piston 12 also back to its initial position. The casting can now be removed from the die cavity 11 and the machine is ready for another casting operation cycle.

The manner in which this venting device is designed and arranged can be varied in numerous ways without departing from the spirit of the invention. For instance, the differential piston 27 can be brought back to its initial position by means of hydraulic pressure acting continuously in bore 39, or under the influence of the force of a spring. The displacement of the piston 27 towards its forward and active position may be effected by other suitable pneumatic, electrical or purely mechanical means. Similarly the control valve 24 can be effected by suitable hydraulic, pneumatic, electrical or mechanical means which may or may not be independent of the circuit which controls the injection phase of the piston 12.

The special arrangement of the valve 24 which controls the escape channel 22 may be applied to a pressure die casting machine which is not provided with a vacuum installation 64.

The special arrangement of the valve 24 described above with reference to the annexed drawings is by way of example shown on a cold chamber pressure die casting machine of the horizontal type. It is clear that this arrangement of the valve 24 can be applied to any other type of pressure die casting machine either hot or cold chamber and with either horizontal or vertical injection piston.

While in accordance with the patent statutes I have described and illustrated the preferred embodiment of my invention now known to me, it will be apparent to those skilled in the art that other changes may be made in the apparatus described without departing from the scope of the invention set forth in the appended claims.

I claim:

1. A venting device for die casting apparatus of the type having a pair of relatively movable die elements having opposed die faces between which is formed a die cavity, at least one of said die faces having a channel therein for evacuating air and gases from the die cavity, comprising valve means secured to the die casting apparatus adjacent and spaced laterally from the die ele- 40

ments, said valve means having a longitudinally movable sleeve therein, means for moving said sleeve longitudinally to cause one end thereof to come into contact with both die elements about the orifice of the die face channel 5 prior to the casting operation and for moving said sleeve away from the die elements when the injection of material into the die cavity is terminated, passage means within said movable sleeve adapted to be connected to a vacuum source for allowing air and gases to be evacuated 10 from the die cavity when said sleeve is in contact with said die elements, and a valve element within said movable sleeve for closing the die channel at a predetermined time during the injection cycle to prevent ejection of material from the die cavity.

15 2. In a die casting apparatus a venting device as defined in claim 1 wherein said movable sleeve comprises a differential piston.

20 3. In a die casting apparatus a venting device as defined in claim 2 wherein the end of said differential piston adapted to contact the die elements has a cavity therein 25 in communication with means for evacuating the die cavity.

4. In a die casting apparatus a venting device as defined in claim 3 wherein the means for evacuating the die cavity includes vacuum means.

25 5. In a die casting apparatus a venting device as defined in claim 3 wherein said valve element includes a longitudinally-movable valve piston colinearly arranged within that end of the differential piston which is adapted 30 to contact the die, said longitudinally-movable piston being adapted to close the orifice of the die channel and thus terminate evacuation of the die cavity.

35 6. Apparatus as defined in claim 5 and further including spring means in said movable differential piston biasing said valve piston out of engagement with the orifice of the die face channel, and bushing means surrounding the shaft of the valve piston for adjusting the tension of said spring means.
